Inventor

Nathaniel Bois
By *A. B. Prosser & Co.*
Attorneys.

UNITED STATES PATENT OFFICE.

NATHANIEL BOIS, OF SAN FRANCISCO, CALIFORNIA.

STAIR STRUCTURE.

1,353,377.

Specification of Letters Patent. Patented Sept. 21, 1920.

Application filed April 12, 1920. Serial No. 373,214.

To all whom it may concern:

Be it known that I, NATHANIEL Bois, a citizen of the United States, residing at San Francisco, in the county of San Francisco, and State of California, have invented certain new and useful Improvements in Stair Structure; and I do declare the following to be a full, clear, and exact description of the invention, such as will enable others skilled in the art to which it appertains to make and use the same.

This invention relates to stair structure, and more specifically to a combination of improved metal stair structure.

The main object of this invention is to generally improve upon devices of this character, and especially to improve upon my prior Patents Nos. 724790, 750156, 1244021 and 1304533, by providing an improved combination which is exceedingly simple in construction, embodying comparatively few and easily formed parts, these parts being exceedingly easily assembled; also combining the improved interlocking features and securing means shown (uncombined) in the several prior patents designated in the foregoing.

Other objects and advantages will be pointed out or implied in the following detailed description in connection with the accompanying drawings, in which:

Figure 1 is a longitudinal vertical sectional view through a portion of stair structure made in accordance with the present invention, the section being taken substantially along the line 1-1 of Fig. 2.

Fig. 2 is a vertical sectional view, the section being taken substantially along the line 2-2 of Fig. 1.

Fig. 3 is a perspective view of one sheet metal step member.

Fig. 4 is a view similar to Fig. 1, but illustrating a somewhat modified form of the invention.

Fig. 5 is a view somewhat similar to Fig. 2, but illustrating the modified form shown in Fig. 4, the section being taken along the line 5-5 of Fig. 4.

Fig. 6 illustrates a modified form used where the soffit is to be plastered.

Fig. 7 is a sectional view along the line 7-7 of Fig. 6.

Fig. 8 illustrates a modified form of combined tread seat and riser.

Referring to these drawings in detail, in

which similar parts throughout the several views are designated by similar reference characters, the invention consists in the combination and arrangement of parts as will now be specifically described and claimed.

In certain forms of this present invention, the stringers 1 are substantially of the form illustrated at 6 in my prior Patent, No. 750156, these stringers being formed with an inwardly projecting flange 2 and an outwardly projecting flange 3, the latter being integral with the upper edge of its stringer, while the former is integral with the lower edge of its stringer, the lower flange being provided with a series of apertures through which securing bolts 4 extend.

The sheet metal step member shown in Fig. 3 combines certain important features illustrated in my prior Patents Nos. 1244021 and 1304533, that is, it combines the interlocking elements 7 and 8 of the former of these patents with the apertured seats or securing elements 9, disclosed by the other one of these prior patents. In this connection, it should be understood that each step member (as shown in Fig. 3) has a tread-supporting element 10 formed with an upwardly and inwardly extending flange 8 at its front edge and at its rear edge it is upwardly inclined as illustrated at 9, and apertured as illustrated at 11, the apertures 11 being adapted to register with those of the flange 2 and to receive the bolts 4. By referring to Figs. 1 and 4, it will be seen that each of the bolts 4, is provided with a nut which is seated on the upper surface of the upwardly inclined portion 9. It will also be seen that the lower surface of each portion 9 is parallel with the flange 2 of each bar or stringer 1, so that a very close and solid connection is obtained between these step members and the flanges 2.

It is to be understood that the ends of the step members fit snugly against the vertical inner surfaces of the stringers 1, so that a substantially non-leakable receiver is formed by the union of the stair members and stringers, and in order to insure such close fitting and to render these receptacles non-leakable, and also to obtain the greatest strength and rigidity consistent with few and simple parts, long bolts or tie rods 12 are employed in a manner somewhat similar to that illustrated in my prior Patent No. 110

724790. However, the bolts are formed, in this invention, with round or convex heads 12^a. The bolts 12 extend from the outer stringer 1 to and through the inner stringer 5 1, these stringers being apertured at 13 for receiving the bolts 12, and the inner end of each bolt 12 is provided with a nut 12^b which is seated against the surface on which the angle-iron or beam 5 is secured. The 10 space between the upper flange 3 and the bar 5 provides ample room for the inner ends of the bolts 12 so that the latter do not interfere with the wall *w* and cannot be interfered with by the wall or any person 15 after the stair structure has been secured in place against the wall.

As in my prior patent, treads 14 may be formed by filling the receptacle with concrete or other plastic material, and these 20 treads 14 not only cover and hide the nuts and the inner ends of the bolts 4, but also prevent these nuts from being turned, and tend to prevent the bolts from being turned, since the upper ends of the latter extend 25 beyond the nuts and are embedded in the concrete or plastic material.

The outwardly projecting flange 3 of the inner stringer 1 provides a plaster-strip or means to define the limit of the lower edge 30 of the plaster above the stairway, and it is clearly within the scope of this invention to provide this upper portion of the inner stringer with a longitudinal groove or channel such as shown at 6. Moreover, it is within the scope of this invention to form 35 the angle-bar 5 integrally with the inner stringer 1, instead of making it primarily separate and attaching it in the manner illustrated. However, the form illustrated 40 is preferable where the stringers are formed from strips of sheet metal and have their edges turned by means of a brake or other appropriate means.

The interlocking means illustrated at 7^a 45 and 8^a, shown in Fig. 4, may be employed in lieu of that illustrated at 7 and 8 in Fig. 1, and other changes may be made within the scope of the claims.

In the modified form shown in Figs. 6 50 and 7, the angle-iron 5 is eliminated from the inner stringer 1, and the outer stringer 1^a has an angle-iron 1^b secured thereto or united therewith by any appropriate means, this angle-iron having an inwardly extending 55 flange on which the tread supporting element 10 rests.

The plaster soffit is indicated at P, the same being applied to metal lath or ex-

panded metal, as indicated at 15, this metal lath being secured in place by the bolts 4 or 60 by any appropriate means.

What I claim as my invention is:

1. In a stair structure, a pair of stringers each provided with an inwardly extending apertured flange adjacent to its lower edge, 65 a plurality of stair steps each formed of a single piece of sheet metal and comprising a horizontal tread-carrying portion and a vertical riser portion, the front edges of the upper tread-carrying portions being interlocked with the upper edges of the riser portions, the junctions of the tread and riser portions being seated on said inwardly extending flanges and provided with apertures that register with those of said flanges, bolts 75 extending through these registering apertures and provided with nuts, treads secured on said tread-supporting portions, and bolts each extending through both of said stringers and substantially throughout the width of 80 the stair structure, each of these latter bolts being disposed directly under the respective tread-carrying portions rearward of the respective interlocking portions of the tread-carrying portions and risers. 85

2. In a stair structure, a pair of sheet metal stringers each provided with an inwardly extending apertured flange adjacent to its lower edge, a plurality of stair steps each formed of a single piece of sheet metal 90 and comprising a horizontal tread-carrying portion and a vertical riser portion, the front edges of the upper tread-carrying portions being interlocked with the upper edges of the lower riser portions, the junctions of 95 the tread and riser portions being parallel with and seated on said inwardly extending flanges and provided with apertures that register with those of said flanges, bolts extending up through these registering apertures and provided with nuts on their upper ends, treads secured on said tread-supporting portions by the interlocking parts of the treads and risers, these treads concealing and guarding said nuts, and bolts each extending through both of said stringers and substantially throughout the width of the stair structure, each of these latter bolts being disposed directly under the respective tread-carrying portions rearward of the respective interlocking portions of the tread-carrying portions and risers. 100 105 110

In testimony whereof I have hereunto set my hand.

NATHANIEL BOIS.
